UNITED STATES PATENT OFFICE.

FRANK W. HOWARD, OF NEW YORK, AND FRANCIS D. AMMEN, OF FLUSHING, NEW YORK.

UMBRELLA RIB AND RUNNER.

1,297,470.

Specification of Letters Patent. Patented Mar. 18, 1919.

Application filed October 5, 1914. Serial No. 865,188.

To all whom it may concern:

Be it known that we, FRANK W. HOWARD and FRANCIS D. AMMEN, citizens of the United States, residing, respectively, at New York, in the county of New York and State of New York, and Flushing, in the county of Queens and State of New York, have invented new and useful Improvements in Umbrella Ribs and Runners, of which the following is a specification.

This invention relates to umbrellas and particularly to the ribs and runners of umbrellas.

A principal object of the invention is to produce an umbrella which will be very efficient but which can be very simply and economically constructed, the general purpose being to enable umbrellas to be manufactured at extremely low cost.

As it concerns the ribs, a principal object of this invention is to provide a construction for the ribs which will enable them to be readily and cheaply constructed by machinery and readily attachable to the umbrella stick or rod, avoiding the necessity for the usual joint at the umbrella crown.

A further object of the invention is to produce an umbrella having a neat and compact construction at the crown.

A further object of the invention is to provide a runner of very simple construction which can be readily and very economically manufactured.

A further object of the invention is to provide a runner which can be very simply locked to the stick in order to enable it to hold the umbrella open, without necessitating the use of the usual means attached to the stick for this purpose.

The invention consists in those features and combination of parts hereinafter described, all of which contribute to produce an efficient umbrella. The invention also resides in the method of constructing the runner and of attaching it to its contiguous parts.

A preferred embodiment of our invention will be particularly described in the following specification while the broad scope of our invention will be pointed out in the appended claims.

In the drawings:—

Figure 1 is a vertical section diagrammatically illustrating an umbrella embodying our invention.

Fig. 2 is a side elevation of a sleeve from which the runner is constructed and illustrating the first step in the process of forming the runner.

Fig. 3 is a vertical section through the complete runner showing certain parts broken away and illustrating the manner in which the runner may be locked upon the stick.

Fig. 4 is a side elevation showing a locking member or key which is a feature of the invention.

Fig. 5 is a plan of the runner showing the ends of the stretchers and illustrating the preferred manner in which they are attached to the runner and also illustrating the stick in cross section.

Fig. 6 is a sectional view in three parts, particularly illustrating the manner in which the parts of the umbrella are assembled in attaching the ribs to the stick.

Fig. 7 is a side elevation showing a modified form of runner.

Fig. 8 is a plan showing a part of the runner illustrated in Fig. 7.

Referring more particularly to the parts, 1 represents the "stick" or rod of the umbrella which may be of steel but which is preferably of wood. For convenience, one end of this stick may be provided with a knob 2 to form a handle. The manner of constructing the ribs of the umbrella will appear most clearly from Figs. 1 and 6. The ribs are preferably formed of light resilient material, such as steel wire, and the ribs are preferably formed with rings preferably in the form of coils and are adapted to hold themselves on the stick. The coils are preferably formed of the same piece of wire with the ribs, the ribs being integrally united with the coils through the medium of an extension having a special form adapting it to flex freely and thus permitting the movement of the rib necessary to open and close the umbrella. The ribs 3 and 4 are preferably formed in pairs, the diametrically opposite pairs being united by a coil, such as the coil 5; the ends of the coils have integral extensions 6 which are formed so as to flex preferably by simply flattening the wire at this point so that the face of the flat portion is toward the stick.

The coil 5^a, which is illustrated in Fig. 6, at the top has short extensions 7 at the end of the coil which extend along the side of

the stick a short distance, and similar short extensions are formed on the coils 5^b and 5^c. The length of the different extensions is different, and is such in each case, that if the coils 5^a, 5^b and 5^c are placed on the stick adjacent to each other, the flattened extensions 6 of the ribs will all lie substantially opposite to each other, that is, their middle points will lie in the same plane transverse to the axis of the stick. When the coil 5^b is put in position, its flexing extensions 6 are placed in a position intermediate of the corresponding flexing extensions 6 of the coil 5^a and likewise as to the coil 5^c so that when all three of the coils have been put on the stick, the flattened extensions 6 are disposed substantially equidistant around the stick, like the stretchers 13 in Fig. 5. These coils are resilient and are preferably of such a diameter that they resiliently grip the stick and hold the ribs securely thereto simply by forcing them onto the stick.

Above the position of the coils when on the stick, we preferably provide a bell-shaped crown piece 8 which receives the central portion 9 of the umbrella cover 10, the said center of the cover being held against the same by a ferrule 11 or any other suitable means seating on the stick.

These ribs 3 and 4 and the coils connecting them are preferably formed by machinery and in order to facilitate the formation of all the parts of the ribs by machinery, we prefer to form eyes 12 in the ribs for the stretchers 13 in the manner indicated in Fig. 1, that is, by bending the wire so as to form inwardly offset loops and then close the loops by jamming the shoulders 14 of the open loops against each other. The outer edges of the cover 10 are attached preferably by rings or eyelets 15 to eyes 16 formed in the ends of the ribs.

The runner used with this improved rib may be of any desired form but we prefer to employ a runner embodying the invention disclosed herein. This runner is preferably formed from a plain cylindrical sleeve 17, one end of which we form with a plurality of slits 18 passing completely through the wall. These slits are preferably diametrically opposite to each other and divide the circumference of the sleeve into a plurality of tongues 19. We then bend these tongues outwardly at their root 20 so that they form outwardly and preferably inclined extensions 21; the function of these extensions is to facilitate the attachment of the runner to the umbrella stretchers 13. In order to accomplish this, we prefer to crimp the ends of the extensions 21 around the ring 22 and between the extensions 21 portions of the ring are exposed as indicated most clearly in Fig. 5, and at these points the stretchers 13 may be con-

veniently attached by forming eyes 23 at their ends adjacent the ring. In this way, a runner is formed of the sleeve with extensions to effect the attachment of the stretchers and at the same time, the ring operates as a reinforcement or strengthening part for the extensions 21. In this way, any unusual force exerting itself as a thrust in the stretcher, will be resisted by all of the extensions because they are tied together by the ring.

In this umbrella, we contemplate omitting any device near the upper portion of the stick for holding the runner up on the stick when the umbrella is in its open condition. For this reason, we prefer to provide the runner with means for clamping it to the stick when it is run up on the stick. To this end, we prefer to provide a simple locking member, such as the bent wire or key 24, which is disposed within the sleeve 25 of the runner in the space between the stick and the wall of the runner, and extends longitudinally of the runner. For this reason, the diameter of the sleeve should be slightly greater than that of the stick. Any suitable means is provided for holding the locking member in position. This is preferably accomplished by forming a slight hook 26 at the upper end of the locking member or key 24 which engages the upper end of the sleeve 25. The lower end of this locking member 24 may have a laterally bent portion forming a handle 27 which enables the locking key to be rotated. The locking key is bent or given any other suitable irregular form, such that when rotated in the proper direction, it will jam against the stick, on one side, and against the inner face of the sleeve on the other side, and by reason of its resiliency clamp the runner securely to the stick.

Instead of employing a locking member of the very simple form described above, we may produce a runner by making a sleeve from a blank tube, such as shown in Fig. 2, but instead of employing a simple ring, such as the ring 22, to attach to the ends of the extensions at the upper end of the sleeve, we may combine the sleeve with a coil or runner device 28, such as illustrated in Fig. 8, and which has been fully disclosed in the co-pending application of Frank W. Howard, one of the co-inventors in the present application. In combining this device 28 with the sleeve, we form slits 29, similar to the slits 18, but these slits 29 are formed from the lower end of the sleeve so that the lower portion or body 30 of the sleeve, as illustrated in Fig. 7, is collapsible. The extensions 31, which are formed in the same manner as the extensions 21, have their ends bent or crimped as at 32 around the ring 33 which forms the upper part of the runner device 28 and this ring 33 is pref-

erably integral with the contractile coil 34 which encircles the sleeve 30 and tends normally to exert a constricting force upon the sleeve, causing it to grip the stick. The 5 ring 33 is of relatively large diameter as compared with the diameter of the body 30 of the sleeve. This facilitates the crimping of the ends of the extensions 31 about the ring 33, because the longitudinal curvature 10 of the crimp is reduced. The runner device 28 is preferably formed of wire and near the ends of the coil this wire is bent so as to present extensions 35 and these extensions operate as finger pieces adapted to 15 be pressed toward each other. When so pressed they tend to open the coil, as will be readily understood. Evidently with a runner constructed in this way, the same opportunity is offered by the ring 33 for attaching the stretchers to the runner as in 20 the embodiment illustrated in Fig. 5.

It is understood that the embodiment of the invention described above is only one of the many embodiments our invention may 25 take, and we do not wish to be limited in the practice of the invention nor in the claims to the particular embodiment described.

What we claim is:

- 30 1. In an umbrella, in combination, a stick, a rib of resilient material having a reduced part adjacent said stick adapted to flex freely to permit an outward and inward movement of the rib in opening and closing the umbrella, said rib having an integral coil adapted to engage said stick to retain the rib thereupon.
- 35 2. In an umbrella, in combination, a stick, a pair of ribs of resilient material having a 40 coil integral therewith connecting the same, and adapted to engage the stick, said ribs having reduced portions adjacent to said stick adapted to flex freely to permit an outward and inward movement of the ribs in opening and closing the umbrella.
- 45 3. In an umbrella, in combination, a stick, a plurality of coils of resilient material disposed near each other upon said stick, said coils having integral ribs extending therefrom with a flattened part adjacent said coils, the flattened parts of said ribs being adapted to flex freely to permit an outward and inward movement of the ribs in opening and closing the umbrella.
- 50 4. In an umbrella, in combination, a stick, a plurality of coils mounted upon said stick,

a pair of umbrella ribs integral with each coil, said ribs having flattened portions adjacent said coils adapted to flex freely to permit an outward and inward movement 60 of the ribs in opening and closing the umbrella.

5. In an umbrella, in combination, a stick, a plurality of coils mounted upon said stick, a pair of diametrically opposite umbrella 65 ribs formed integrally with the two ends of each of said coils, said ribs having flattened portions adjacent said coils adapted to flex freely to permit an outward and inward movement of the ribs in opening and clos- 70 ing the umbrella.

6. In an umbrella, in combination, a stick, a plurality of coils mounted upon said stick, a pair of umbrella ribs integral with each coil, said ribs having flattened portions ad- 75 jacent said coils adapted to flex freely to permit an outward and inward movement of the ribs in opening and closing the umbrella, said flattened portions being disposed substantially opposite to each other in a 80 plane transverse to the stick.

7. In an umbrella, in combination, a stick, a runner consisting of a sleeve mounted to slide on said stick, said sleeve having a plurality of outwardly bent integral extensions 85 to be attached to the umbrella stretcher, and a locking key extending longitudinally with the runner, carried in the space between the stick and said sleeve, said locking key being of bent form and operating when rotated to 90 press against the side of the stick and against the inner face of said sleeve, thereby jamming the sleeve on the stick.

8. In an umbrella, in combination, a stick, 95 a plurality of ribs separate from said stick having integral means for engaging the stick to secure the ribs thereto, said ribs having integral portions adjacent the stick extending substantially longitudinally of the stick and disposed substantially equidistant around 100 the stick, said portions being adapted to flex freely to permit the movement of the ribs in opening and closing the umbrella.

In testimony whereof we have hereunto set our hands in presence of two subscribing 105 witnesses.

FRANK W. HOWARD.
